CLAIM

The ornamental design for a robot, as shown and described.

DESCRIPTION

FIG. 1 is a perspective view of a robot;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom view thereof; and,

FIG. 8 is another perspective view of the robot in an alternate position.

The broken lines in the drawings illustrate the portions of the robot that form no part of the claimed design.
